United States Patent [19]
Gamm

[11] Patent Number: Des. 281,738
[45] Date of Patent: ** Dec. 17, 1985

[54] ATHLETIC SHOE FOR KICKER

[75] Inventor: Robert J. Gamm, St. Louis County, Mo.

[73] Assignee: Kangaroos U.S.A., Inc., St. Louis, Mo.

[**] Term: 14 Years

[21] Appl. No.: 519,037

[22] Filed: Aug. 1, 1983

[52] U.S. Cl. D2/311; D2/308;
D2/313

[57] CLAIM

The ornamental design for the athletic shoe for kicker, as shown and described.

DESCRIPTION

FIG. 1 is a top and left-front perspective view of an athletic shoe for kicker showing my new design;
FIG. 2 is a top plan view thereof;
FIG. 3 is a left side elevational view thereof;
FIG. 4 is a right side elevational view thereof;
FIG. 5 is a bottom plan view thereof;
FIG. 6 is a rear elevational view thereof;
FIG. 7 is a front elevational view thereof.
